MACHINE FOR EXPANDING HOLLOW ARTICLES

Alexis E. Ushakoff, Beverly, Mass., assignor to
United Shoe Machinery Corporation, Flemington, N. J., a corporation of New Jersey

Application May 8, 1941, Serial No. 392,482

2 Claims. (Cl. 18—19)

This invention relates to machines for expanding hollow articles or blanks and is herein illustrated as embodied in a machine for expanding by heat and pressure a thin-walled, hollow cover blank to desired shape and for freezing it in that shape preparatory to placing a heel in the expanded blank and heating it to cause it to shrink about the heel.

In United States Letters Patent No. 2,236,552, granted April 1, 1941, upon an application filed in my name, there is disclosed a hollow heel-cover blank made of macromolecular material in the form of a swollen gel which is capable of stretching somewhat and will shrink by loss of liquid. There are described in said Letters Patent two methods of using such a blank in the cover of a heel. According to one method, referred to therein as the dry method, a block of circular outline is placed in the mouth of the cover blank while the blank is in swollen gel form, and the blank with the block in its mouth is put aside and allowed to shrink, the function of the block being to keep the mouth open and of a desired size. A machine for inserting such a block is disclosed in United States Letters Patent No. 2,296,964, granted September 29, 1942, upon an application filed in my name. Later the blank is expanded by means of heat and pressure and frozen in expanded shape; and finally a heel is placed in the blank, and the blank is heated to cause it to shrink while at the same time a partial vacuum is created in it so that the shrunken blank will conform exactly to the shape of the heel.

According to the present invention a machine is provided for expanding a hollow article or blank by heat and pressure and freezing it in expanded shape. The illustrated machine has a nozzle over which the mouth of the blank is placed, means for clamping the mouth to the nozzle and for enclosing the blank in a mold, and means for thereafter forcing first a hot fluid and then a cold fluid into the blank.

Referring to the accompanying drawings,

Fig. 1 is an end elevation of a machine in which the present invention is embodied, part of the casing and the frame being shown in vertical section, and a heel cover blank being shown in place with its mouth over the nozzle of the machine;

Fig. 2 is a front elevation of the machine, part of the casing, frame and cylinder being shown in vertical section;

Fig. 3 is a detail in vertical section on an enlarged scale of the nozzle, a heel cover blank being shown in place; and

Fig. 4 is a detail also in vertical section and on an enlarged scale showing the nozzle and the mold, there being in the mold an expanded heel cover blank.

5 The purpose of the machine, as has been stated, is to expand a hollow blank by means of heat and pressure and to freeze it in expanded shape; and, before describing the machine in detail, a general description of its mode of operation will 10 be given. The blank 100 has a comparatively large, circular mouth and has extending from its closed end a slender, solid projection 209 which was formed in the sprue of the molding machine in which the blank was made. In the operation 15 of the machine a blank is placed with its mouth over a nozzle 7, said mouth having been made of such a size and shape that it fits the nozzle fairly closely. The blank is centered to an extent, if necessary, in a manner presently to be described, 20 by means of a vertically slidtable, slender tube 9 (Fig. 1); and then a hollow mold, which comprises an open-ended portion 11 and a bottom 13, is brought down into the position shown in Fig. 4 in which the wall around the mouth of 25 the blank 100 is clamped between the tapered outer surface of the nozzle 7 and the tapered inner surface of the hollow mold 11 in such manner as to form an air-tight joint, the tapers on the mold and on the nozzle being so constructed 30 as to limit further downward movement of the mold. With the blank so held, hot air, forced in through a conduit 15, flows out through a pipe 17 and thence through a valve, hereinafter described, whereby the outflow of air may be restricted as desired to control the pressure of the 35 hot air in the blank. This compressed hot air heats the blank and expands it against the inside of the mold as shown in Fig. 4. As soon as the blank has thus been expanded, the supply of 40 hot air is cut off, and cold air, which may be at room temperature, is forced through a conduit 19 and through connected ports 21 in the nozzle 7 into the blank to freeze it, said cold air flowing out through the same conduit 17 through which the 45 hot air flowed out. The operation on the blank is now complete, the mold is raised and the blank is removed. The general mode of operation of the machine having been thus briefly outlined, a detailed description of the machine will now be 50 given.

Referring to Figs. 3 and 4, the nozzle 7 is a block circular in cross section and has extending vertically through it a bore 29 of larger diameter than that of the hot air conduit 15. It also has vertical ports 21 which are connected by a port

23, the latter being in communication with the cold air conduit 19. The nozzle is fastened to the upper flanged end of a generally spool-shaped member 25 by screws 27, the lower flanged end of the member 25 being fastened by screws 29 to a heavy stationary plate 31 (Figs. 1 and 2) which is supported on the top of a frame, said frame comprising uprights 33 and cross pieces 35. Referring again to Figs. 3 and 4, the receiving end of the conduit 17, through which the hot air and the cold air flow out, is threaded into a hollow boss on one side of the spool-shaped member 25; and directly opposite there is threaded into another hollow boss a conduit 37 which leads to a pressure gage 39 (Figs. 1 and 2).

The open-ended portion 11 of the hollow mold has at its lower end a flange which fits into a rabbit on the inner wall of an annular supporting member 41, said flange being clamped to the supporting member by a ring 43 and nuts 45 threaded on four small upright rods 47, the lower ends of which pass through holes in the ring and are threaded into the annular member 41. The open-ended portion 11 of the mold is preferably made of metal. The bottom 13 may be a thick sheet or plate of transparent resin square in outline and having large holes through which the slender rods 47 pass. The bottom of the mold is held down against the smaller end of the open-ended portion 11 by four compression springs 49 which surround the slender rods 47, the lower ends of the springs resting upon washers 51 and the upper ends being in contact with nuts 53 which are threaded on the rods 47. Resting upon the four nuts 53 is a thin plate 55 which is fastened in place by nuts 57. The thin plate has in its center a bore of larger diameter than that of the slender tube 9, the tube extending through this bore and through a bore in the bottom 13 of the mold. When the mold is in raised position (Figs. 1 and 2) the tube 9 is suspended from the thin plate 55 by its head which is too large to pass through the bore in this plate.

The blank 100, as has been explained, was in the form of a swollen gel when it was made and was allowed to shrink, a block of proper shape having been first placed in its mouth to hold the mouth open. During this shrinking, the blank sometimes becomes somewhat deformed so that the slender projection 200 is off center. The purpose of the tube 9 is to facilitate centering the blank approximately when it is in the position shown in Fig. 1 after having been placed with its mouth over the nozzle 7 and before the mold has been moved down over it. To accomplish this, the blank is placed with its mouth over the nozzle, then the lower end of the pipe 9 is placed over the projection 200, the bottom 13 of the mold being slid horizontally to permit this, and finally the bottom is slid back into proper position, the sliding of the bottom being permitted by reason of the fact that the holes through which the rods 47 pass are enlarged and that the bottom is yieldingly held in place by the springs 49. The springs 49 obviously do not exert a very great pressure upon the plate or bottom 30 of the mold, since the plate may readily be slid horizontally to permit positioning of the pipe 9; and, by manipulating the valve 113 to regulate the pressure of compressed hot air, said pressure may be caused to lift the bottom 13 slightly, if desired, during the momentary expanding of the blank.

The annular member 41, which supports the whole mold structure, is fast to the upper ends

of three rods 59 which are vertically slidable (Fig. 2) in bores formed in the stationary plate 31 and in upwardly projecting bosses on said plate, the lower ends of said rods being fastened to a circular plate 60 which is carried at the upper end of a piston rod 61, the lower end of said rod carrying a piston, indicated as a whole at 63, said piston being adapted to reciprocate in a vertical cylinder 65 which is suspended rigidly from the stationary plate 31 by means of vertical tie-rods 67. When a blank to be expanded has been placed in position as shown in Fig. 1, compressed air causes the piston 63 to descend and pull down the whole mold structure into the position shown in Fig. 4. Thereafter, hot air is forced into the blank to expand it, as shown in Fig. 4, then cold air to freeze it, and finally the piston 63 raises the whole mold structure into the position shown in Figs. 1 and 2 and the machine comes to rest. The machine is operated entirely by compressed air.

Assuming that the machine has come to rest and that a blank 100 has been put in place as shown in Fig. 1, the machine is operated by first 25 swinging a hand-lever 69 (Fig. 2) in one direction which admits compressed air to the top of the cylinder 65 and exhausts air from the bottom of the cylinder so that the mold is brought down over the blank. After this there is pushed 30 down a button 71 at the upper end of a valve rod 73, whereupon compressed hot air is forced into the blank to expand it. Next there is pushed down a button 75 at the upper end of a valve rod 77, whereupon compressed, unheated or cool 35 air is forced into the blank to freeze it in its expanded shape; and finally the hand-lever 69 is swung back to its original position, whereupon the piston raises the mold structure to the position shown in Figs. 1 and 2.

40 Two conduits 79, 81 for compressed air connect respectively the upper and the lower ends of the cylinder 65 with a valve mechanism of commercial form, the details of construction of which form no part of the present invention. 45 This mechanism comprises a casing 83 to which compressed air is supplied continuously through a conduit 85; and in the casing are suitable valves controlled by the handle 69 which has been referred to above. When the handle is at one 50 limit of its swinging movement, compressed air flows through the conduit 81 to the bottom of the cylinder, the top of the cylinder being exhausted through the conduit 79; and when the handle is swung to the other limit of its movement, the 55 reverse takes place. The exhaust, whether from the top or from the bottom of the cylinder, emerges from the casing 83 through a conduit 87 and is delivered through a T 89 and a conduit 91 into the upper end of a muffler 93.

60 The compressed air which is forced into the blank is supplied through a conduit 95 and passes into a horizontal conduit 97. Leading from the latter conduit are two conduits, one for air which is to be heated and one for cold air. The conduit 65 for air which is to be heated has in it a valve 99 which is normally held closed but may be opened by pushing down on the button 71 in the upper end of the valve rod 73. The conduit for air which is not to be heated has in it a similar valve 101 which may be opened by pushing down the button 75 at the upper end of the valve rod 77. The lower ends of the valve rods 73, 77 are connected with their respective valves in the same manner, the connection of the rod 77 with its valve being shown in Fig. 1 wherein said rod is

pivoted to the outer end of an arm which rests upon the top of the stem of the valve, the inner end of the arm being pivoted to a stationary bracket 103. When the valve 99 is opened, compressed air, which is supplied from the conduit 95, flows through a conduit 105 into the bottom of a heater 107, then up through the heater and out of its upper end through a conduit 109 which leads into the bottom of a second heater 111, then up through that heater and out of its upper end into the conduit 15 which (Fig. 3) terminates in the nozzle 7. Referring now (Figs. 1 and 2) to the conduit 95 through which compressed air is supplied for heating and expanding and then cooling the blank, if the button 75 at the upper end of the valve rod 77 is pushed down to open the valve 101, the unheated air passes up through the conduit 19 which leads (Fig. 3) into the nozzle. As has been noted, both the hot air and the cool air flow out of the blank through the conduit 17. Referring now to Fig. 2, this conduit leads down into the same T 89 into which the exhaust conduit of the cylinder 65 leads. In order to be able to raise and lower the pressure of the air in the blank, this conduit 17 has in it a valve 113 which may be opened more or less as may be desired by turning a hand wheel 115, the pressure being indicated by the pressure gage 39. In order to prevent the exhaust from the cylinder 65 through the conduit 87 from flowing up through the conduit 17 and thereby interfering with the outflow of air from the blank, a check valve 117 is located in the conduit 17. The air heaters 107 and 111 may be of any suitable type, those shown containing electrical heating units.

The operation of the machine is briefly as follows. With the parts of the machine in the positions shown in Figs. 1 and 2, the operator places the mouth of a blank 100 over the nozzle 7 with the lower end of the tube 9 over the projection 200, as shown in Fig. 1. He then swings the hand-lever 69 in one direction to cause the mold to be brought down into the position shown in Fig. 4 to enclose the blank and to clamp its mouth to the nozzle 7. Next he pushes down the button 71 to cause hot compressed air or other fluid to be admitted to the interior of the blank to expand it against the interior of the mold as shown in Fig. 4, the fluid flowing out through the conduit 17, this outflow having been restricted to give the desired pressure in the blank by adjustment of the valve 113 in said conduit. Next

he releases the button 71 and immediately pushes down the button 75 to cause cold or unheated fluid to be admitted to the interior of the blank to freeze it in expanded shape, said fluid flowing out through the same conduit 17 as did the hot fluid. The button 75 is then released, and the hand-lever 69 is manipulated to return the parts of the machine to the positions shown in Figs. 1 and 2, whereupon the expanded and frozen blank, which usually remains with the mold, is removed.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

20 1. A machine for expanding a hollow blank having a mouth, said machine having in combination a tapered nozzle over which the mouth of the blank is placed, a mold-support reciprocable toward and from the nozzle and normally held away from the nozzle a distance greater than the height of the blank to permit the blank to be placed with its mouth over the nozzle, a mold carried by said mold-support, said mold having a tapered mouth to fit over the tapered nozzle, an actuator for the mold-support located upon the side of the nozzle opposite to that upon which the mold support is located, means for moving the actuator away from the nozzle to cause the mold to enclose the blank and to clamp the mouth of the blank to the nozzle, and means for admitting fluid under pressure through the nozzle to expand the blank.

25 2. A machine for expanding a hollow blank having a mouth, said machine having in combination a nozzle to receive the mouth of the blank, a mold adapted to clamp the mouth of the blank to the nozzle, said mold comprising a hollow member the mouth of which extends over the nozzle, a bottom member extending over and normally closing that end of the hollow member remote from the nozzle, yielding means tending at all times to hold the bottom member in contact with the said end of the hollow member of the mold to close the opening in said end, and means for admitting fluid under pressure through the nozzle.

ALEXIS E. USHAKOFF.
